ABSTRACT: A wick, inserted into a container of water, so arranged that the wick enters the bottom of the duct into the air filter, wick resting in a trough so constructed that the sides and rear of the trough are raised to restrict the suction of water into the carburetor of an internal combustion motor.

FIG.1

FIG.2

FIG.4

FIG.3

FIG.5

INVENTOR.

Hank B. Otto

**SUPPLY VAPOR TO THE CARBURETOR, FOR
INTERNAL COMBUSTION MOTORS**

My invention relates to a means by which water is available to be converted into vapor by the introduction of heated air into the intake of the duct used to supply the air to the carburetor. The introduction of vapor completely eliminates carbon, the result being that hydrocarbon and carbon monoxide are not present in the exhaust. Automotive engineers are conversant with this fact.

A further object of this invention is to have a supply of water so arranged that the water can be converted to vapor, also with provision that all excess water will drain out of this duct thereby restricting any possibility of the water entering the carburetor throat. The amount of water to supply the vapor is controlled by the size of the wick employed to bring the water up from the water container into the intake duct.

With the above and other objects in view, the invention consists in the novel features of construction, arrangement and combination of the parts, hereinafter more fully described and finally pointed out in the claims hereto appended.

Referring to the drawing:

FIG. 1 is a side elevation view, showing the water container positioned at the bottom of the air intake duct.

FIG. 2 is a plan view, showing the position of the wick in the duct.

FIG. 3 is a side view, showing the position of the wick in the water container.

FIG. 4 is a front view, showing the duct opening to the carburetor and position of the wick.

FIG. 5 is a plan view of the water container divorced from the air duct without the wick showing.

Referring to the drawing: 1 designates the wick, 2 designates the trough and the extension into the water container, 3 designates the water container, 4 designates the cap on the opening for filling the water container, 5 designates the duct to the carburetor, 6 designates the end of the duct to the carburetor, 7 designates the air opening to the duct, 8 designates opening in the floor of the duct, 9 designates opening in the top of the water container.

FIG. 1 is a side elevation view of my invention. 1 designates a wick or any material with capillary attraction. 2 designates a rustproof guide to convey the wick to the bottom of the water in the container, the section of this guide that extends through the bottom of the air duct is so constructed that the sides and the rear of this guide are raised the thickness of the wick forming a trough, any excess water on this wick will drain back into the water container. The wick is attached to this guide in any conventional manner. 5 designates the air duct to the carburetor. 7 designates the opening to the air duct. 6 designates the air exit to the carburetor.

FIG. 2 is a plan view of my invention. 1 designates the wick after entering the air duct. 2 designates the guide which is so constructed with a lip on the sides and rear said lip to be the thickness of the wick. 8 designates the hole cut in the floor of the duct for admitting the guide and wick into the floor of the air intake duct. 3 designates the water container. 4 designates the cap closure for filling the water container. 5 designates the air duct to the carburetor. 7 designates the opening to the air

duct. 6 designates the point at which air passes out of the air duct to the air filter or to the carburetor.

FIG. 3 is a side view of the device. 3 designates the water container. 2 designates the guide to which the wick is attached. At the top of this drawing is shown the raised sides of this guide forming a trough in which the wick is positioned. 1 designates the wick. 4 designates the screw type filler cap.

FIG. 4 is a view looking into the air duct to the carburetor. 7 designates the opening for air to enter the duct. 1 designates the wick. 2 designates the guide. 3 designates the water container. 4 designates the screw type filler cap. 5 designates the opening for air to enter the air duct.

FIG. 5 is a plan view showing the opening 9 in the top of the water container. 4 designates the filler cap opening for filling the water container. 3 designates the water container.

In carrying out the invention, it is my aim to provide a supply of water in the intake duct, so arranged that by drawing hot air over this water supply vapor is formed. 1 is shown as a wick or any material with capillary attraction. 2 designates the guide to which the wick is attached in any conventional manner, this guide extends from the base of the water container 3 up through the water in the container and out at the top through opening 9 as shown in FIG. 5. The guide 2 is inserted into the floor of the air duct through an opening of sufficient dimensions to accommodate the guide with the wick attached.

This guide is so constructed that the wick rests in a trough as shown in the top of FIG. 3, this trough being slightly raised on the sides and in the rear, to the thickness of the wick, all excess water will drain back into the water container 3. The air flow is designated by arrows, the rear of the trough is raised approximately the thickness of the wick allowing air to pass against the wick but not through the wick. This construction permits hot air to pass over the wick 1 and convert the water to vapor allowing a perfect combustion mixture. Without the raised sides and rear of the trough it is conceivable that the terrific suction of the air on the intake stroke could draw water through the wick and allow water to enter the carburetor throat. Any conventional heating device capable of producing approximately 140° F. will extract the moisture on this wick and convert same to heated vapor.

To protect the container of water from freezing add sufficient alcohol.

What I claim:

1. A vaporizer comprising a closed container filled with water, said container having an aperture in the top thereof, an air duct having an inlet and an outlet, an aperture in the bottom of said air duct, said container connected to said duct to provide fluid communication therebetween through said respective apertures, a guide in said container and extending through said apertures into said air duct, the portion of said guide in said air duct being inclined upwardly toward said air duct outlet, said guide defining a trough having said walls and a rear wall at its uppermost end, a wick extending substantially the length of said guide and attached thereto, said wick being positioned within said trough, the sidewalls and the rear wall of said trough having a height equal to the thickness of said wick, means defining an opening in the top of said container and closure cap means for closing said opening.
